John F. Rathbone, Albany, N.Y.
Letters Patent (Design No. 50) dated 5th July 1846

The Schedule referred to in these Letters Patent and making
part of the same.

To all whom it may concern:

Be it known that I, John F. Rathbone of Albany in the County of Albany, and State of New York, have invented or produced a new design for an air tight stove, and I do hereby declare that the following is a full, clear and exact description of the same, reference being had to the accompanying drawing making part of this specification -

Fig. 1, is a perspective view of a stove after my design - Fig. 2 exhibits a portion of the mouldings upon the cap &c &c; and Fig. 3, a section of the same.

-2

Des. 50

Fig 3 is in like manner, a portion of the base mouldings, b b, and Fig. 5, a section thereof.

Fig. 6, is the register c c and Fig. 7, a portion of the door ^{door} frame, d d —
The body of the stove is of sheet iron —

What I claim as my invention and desire to secure by Letters Patent, is the combination and arrangement of ornamental figures herein shown and described, forming a design for an airtight stove
